UNITED STATES PATENT OFFICE.

FRANK W. SACHSE, OF COLUMBUS, OHIO.

HINGE.

1,183,596.

Specification of Letters Patent.

Patented May 16, 1916.

Application filed July 22, 1915. Serial No. 41,388.

To all whom it may concern:

Be it known that I, FRANK W. SACHSE, a citizen of the United States, residing at Columbus, in the county of Franklin and State of Ohio, have invented certain new and useful Improvements in Hinges, of which the following is a specification.

My invention relates to hinges and has particular bearing on the type of hinges used in connection with casement windows or other similar swinging portions, such as doors and the like.

The main object of my invention resides in a structure whereby the window or other object to which my hinge is applied may be locked in any one of various numbers of positions of adjustment between closed end wide open position. This I aim to accomplish without the use of any bunglesome attachments and one which will be positively operable each time its operation is desired.

The preferred embodiment of my invention is shown in the accompanying drawings, in which similar characters of reference designate corresponding parts, and in which:

Figure 1 is a face view of my improved type of hinge showing the same in locked wide open position, Fig. 2 is a similar view showing the leaves in partially closed and unlocked position, Fig. 3 is a section taken on line 3-3 of Fig. 1, Fig. 4 is a section taken on line 4-4 of Fig. 1, Fig. 5 is a side view of the hinge pivot pin showing the locking lever pivoted thereto, Fig. 6 is a view taken at right angles to that shown in Fig. 5, and, Figs. 7 and 8 are side views of the leaves forming the hinge shown detached.

In these several views, the hinge leaves are designated by the reference numerals 1 and 2, each of these leaves having their adjacent edges rolled or folded to present interlocking knuckles such as shown at 3, these knuckles serving the purpose of forming a pivot connection for the pivot pintle 4. The upper knuckle of the leaf 1 is provided with a notched portion such as is shown at 5 to coöperate with a similarly formed fin 6 formed on the upper end of the pivot pintle 4 directly beneath its head 7. This fin and notch arrangement is provided in order to prevent the natural working out of the pintle 4 during the operation of the hinge, the notched portion 5

being usually provided on that part of the hinge which remains stationary. Each of the leaves 1 and 2 is cut out as is shown at 8 and 9 respectively, these cut out portions being designed to accommodate the free movement of locking disks 10 and 11.

Reference to Figs. 3 and 4 will show that the locking disk 10 is provided with a notch 12 so arranged as to embrace the leaf 2 to establish a rigid connection therewith and by means of the slot 8 this disk is movable with regard to the leaf 1. The disk 11 is similarly formed, but its notch 13 is arranged to embrace the leaf 1 and it has no connection with the leaf 2 inasmuch as it operates in the slotted portion 9. The disk 10 is additionally provided with a series of notches 14, while the disk 11 is provided with a single notch 15, these notches being designed to coöperate with a locking lever 16 preferably pivotally carried by the head portion 7 of the pintle 4, as is shown at 17. It will be noted that both the disks 10 and 11 are each provided with a central aperture through which the pintle 4 passes and the arrangement of disks is such that one is in rigid connection with one leaf, while the other is in rigid connection with the other leaf. Therefore, when the hinge is applied to a window or the like, movement of the leaf 2 about its pivot point will move the various locking notches 14 in a path beneath the locking notch 15 carried by the disk 11, which normally remains stationary. It will, therefore, appear that the two leaves may be held in any one of a number of locked positions by simply lifting the pivoted lever 16 out of engagement with the registering notches 14 and 15 as is shown in Fig. 1 and then moving this leaf to any other desired position of attachment to bring any set of notches 14 and 15 into registry and then dropping the lever back into locking position similar to that shown in Fig. 1. By this arrangement the major portion of the hinge structure is practically identical with what is now on the market, the essential difference being in the arrangement of notches 8 and 9 and the shortening of certain of the knuckle portions 3 to accommodate the mounting of the locking disks 10 and 11. Also by this arrangement, a structure is provided whereby a window or other swinging part may be locked in either closed

or open position and this structure occupying a comparatively small compass. By locking the pintle in connection with one of the leaves as regards its rotative movement and pivoting the locking lever to this pintle, the pintle is always in a position to drop into the single notch in the disk 11, which is also held stationary with the leaf 1.

What I claim, is:

- 10 1. A hinge comprising a pair of leaves formed with interlocking knuckle portions along adjacent edges, each leaf having a cut-out portion extending inwardly from said knuckle portions, said two cut out portions being at different elevations so as not to register when said leaves are assembled, a pintle passing through said knuckle portions to pivot said leaves together, a pair of locking disks, one for each leaf and each formed with a cut out portion to embrace its respective leaf whereby a rigid connection is established between said disks and their respective leaves, the rigidly connected disk of one leaf being slidable through the cut out portion of the other leaf, one of said disks being formed with a series of locking openings and the other disk being formed

with a single locking opening, and a lever element arranged to seat itself in any pair of registering locking openings.

2. A hinge comprising a pair of leaves formed with interlocking knuckle portions along adjacent edges, a pintle passing through said knuckle portions to pivot said leaves together, means whereby said pintle is held rigid with one of said leaves as regards rotative movement, a pair of locking disks, one for each leaf and each formed with a cut out portion to embrace its respective leaf whereby a rigid connection is established between said disks and their respective leaves, one of said disks being formed with a series of locking notches and the other disk being formed with a single locking notch, and a locking lever pivoted at one end to the top of said pintle and shaped to seat itself in any pair of registering locking notches.

In testimony whereof I affix my signature in presence of two witnesses.

FRANK W. SACHSE.
